SMOKER'S DRY-PIPE PIN

Ralph G. Kaufman, New York, N. Y.

Application April 11, 1938, Serial No. 201,287

4 Claims. (Cl. 131—208)

This invention relates to new and useful improvements in a smoker's dry pipe pin.

More specifically, the invention proposes the construction of a dry pipe pin characterized by a length of wire bent intermediate of its ends and having a pair of diverging fingers engageable into the smoke passage of a stem bit at the union between the bowl and stem, and upon one end of which a cylindrical filter member is mounted for extending into the smoke passage of a bowl section of a pipe at the union between the bowl and stem for absorbing the moistures from the smoke, and for keeping the heel of the pipe bowl dry.

Still further it is proposed to arch portions of the length of wire which are adapted to engage the cylindrical filter member for the purpose of centering and suspending the filter in the stem of the bowl to absorb moisture from the smoke, and still allow a free passage for the smoke through smoke passage.

Another object of this invention is to form the wire, at its intermediate portion, with an end loop and bulged out portions between which the cylindrical filter member may be engaged for holding it in position within said smoke passage.

Still further it is proposed to form the filter member from filter paper or other similar absorbent material which is rolled into a cylindrical shape, and which has its outer edge extending radially therefrom for contacting the bottom wall of the smoke passage to lift the moisture off the bottom wall and carry it to the body of the filter member.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a cross section of a pipe having a dry smoke pin according to this invention inserted therein.

Fig. 2 is a side elevational view of the dry smoke pin per se.

Fig. 3 is a view looking in the direction of the line 3—3 of Fig. 2.

Fig. 4 is a perspective view of the pin and the filter in their separated condition.

Fig. 5 is a perspective view of the device.

The smoker's dry pipe pin, according to this invention is to be used in conjunction with any average size pipe having a bowl 10 and a stem

11. The stem 11 comprises a bowl section 11a and a stem bit section 11b. The adjacent ends of the bowl section and the stem bit section are connected together in end alignment by means of a reduced shoulder 12 formed on the inner end 5 of the bit section and which is engageable into a complementary opening 13 formed in the outer end of the bowl section 11a.

The dry pipe pin comprises a length of wire 14 which is bent intermediate of its ends to have a 10 pair of diverging fingers 14a which are engageable into the smoke passage 15 of the pipe and within this bit section at the union between said bowl and stem. A cylindrical filter member 16 is supported upon the length of wire at its bent 15 intermediate portion and is engageable into the smoke passage 15 at the bowl section 11a of the pipe. The base ends of the fingers 14a are formed with an offset portion which continues into corresponding elements for engaging and 20 holding the cylindrical filter in position.

The cylindrical filter member comprises a piece 25 of filter paper or other similar material which is rolled into the form of a cylinder and which is supported upon the length of wire for absorbing excess moistures from the smoke which passes through the smoke passage 15. The gripping elements for holding the cylindrical filter comprises an end loop portion 14b, and a pair of oppositely disposed bulged out portions 14c which 30 are capable of engaging around the sides of said filter member. The end loop portion 14a and the bulged out portions 14c are connected together by portions of the wire which are adapted to extend longitudinally along the side of the filter on either side of its end 16a for holding this end 35 radially extended to contact the bottom wall of the passage 15.

The opening 13 is slightly longer than necessary to accommodate the reduced shoulder 12 40 formed on the inner end of the bit section, as shown in Fig. 1, and the filter member is adapted to extend into that portion of the opening 13 which extends beyond the end of reduced shoulder 12.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A smoker's dry pipe pin, comprising a length of wire having its ends formed into a pair of diverging fingers engageable in the smoke passage at the bowl end of the stem bit of a pipe to hold the device in position, a cylindrical filter member for engaging in the smoke passage at the bowl section of the pipe stem, and gripping elements formed in said wire and engaging said filter for holding said filter.
- 5 2. A smoker's dry pipe pin, comprising a length of wire having its ends formed into a pair of diverging fingers engageable in the smoke passage at the bowl end of the stem bit of a pipe to hold the device in position, a cylindrical filter member for engaging in the smoke passage at the bowl section of the pipe stem, and gripping elements formed in said wire and engaging said filter for holding said filter, said gripping elements comprising an end loop formed at the intermediate portion of said length of wire for encircling one end of said filter member, portions continuing from said end loop and extending along the side of said filter, bulged out portions continuing from the ends of said portions and engaging around the other end of said filter member, and offset portions continuing from said bulged out portions and extended over the end of said filter member, said fingers continuing from the ends of said offset portions.
- 10 3. A smoker's dry pipe pin, comprising a length of wire having its ends formed into a pair of diverging fingers engageable in the smoke passage at the bowl end of the stem bit of a pipe to hold the device in position, a cylindrical filter member for engaging in the smoke passage at the bowl section of the pipe stem, and gripping elements formed in said wire and engaging said filter for holding said filter, said filter member comprising a piece of filter paper or other similar material rolled into cylindrical form and inserted between the gripping elements of said wire.
- 15 4. A smoker's dry pipe pin, comprising a length of wire having its end formed into a pair of diverging fingers engageable in the smoke passage at the bowl end of the stem bit of a pipe to hold the device in position, a cylindrical filter member for engaging in the smoke passage at the bowl section of the pipe stem, and gripping elements formed in said wire and engaging said filter for holding said filter, said gripping elements being formed with oppositely disposed arches for engaging said filter member for suspending and centering said filter member within said smoke passage for adequately removing the moisture from the smoke and still permit a free passage for the smoke through the smoke passage.
- 20 25 RALPH G. KAUFMAN.
